ORNAMENTAL CANDLE OR SIMILAR ARTICLE

Winnie R. Nitschke, Austin, Tex.

Application February 17, 1955, Serial No. 34,562

Term of patent 14 years

(Cl. D73—1)

Fig. 1.

Fig. 2.

Fig. 1 is a side elevational perspective view of an ornamental candle or similar article illustrating the design of my present invention, and

Fig. 2 is a view similar to that of Fig. 1 illustrating the design of my present invention as viewed from the rear or reverse side of the showing of Fig. 1.

Each ornamental candle or similar article of my present invention presents substantially the same appearance when viewed from any and all sides thereof, the design thereof being susceptible of reproduction to provide a plurality or succession of ornamental candles or similar articles all of which possess substantially the same ornamental appearance.

I claim:

The ornamental design for an ornamental candle or similar article, as shown and described.
